US0D1091817S

(12) **United States Design Patent** (10) Patent No.: **US D1,091,817 S**
(45) Date of Patent: ** Sep. 2, 2025

(54) **SUCTION FOR ELECTROCAUTERY**

(71) Applicant: **WINDPOSE Co., Ltd.**, Seoul (KR)

(72) Inventor: **Chang Jin Lim**, Guri-si (KR)

(73) Assignee: **WINDPOSE Co., Ltd.**, Seoul (KR)

(**) Term: **15 Years**

(21) Appl. No.: **29/947,117**

(22) Filed: **Jun. 13, 2024**

(30) **Foreign Application Priority Data**

Dec. 15, 2023 (KR) 30-2023-0051303

(51) **LOC (15) Cl.** **24-01**

(52) **U.S. Cl.**

USPC **D24/112**

(58) **Field of Classification Search**

USPC D24/140, 143, 144, 146, 112, 108

CPC A61B 18/1482; A61B 1/0008; A61B 17/1631; A61M 37/0076

See application file for complete search history.

(57) **CLAIM**

The ornamental design for a suction for electrocautery as shown and described.

DESCRIPTION

FIG. 1 is a perspective view of the suction for electrocautery showing the new design;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

1 Claim, 5 Drawing Sheets

FIG. 1

FIG. 2

FIG. 3

FIG. 4

FIG. 5

FIG. 6

FIG. 7
